ROBERT E. MILLER, OF BRONXVILLE, NEW YORK.

FRAME SHELF.

Application filed April 1, 1927. Serial No. 180,172.

My present invention relates generally to shelves, and has particular reference to that type of shelf which is of a generally frame-like and collapsible structure to permit easy 5 shipment and employment thereof.

One object of the invention lies in providing a shelf of this general character wherein in certain structural features greatly increase the staunchness and durability of the 10 shelf.

Another object of the invention is to provide a shelf having an extension arm adjustably associated therewith in a manner which permits varied positioning of the shelf 15 with respect to a suitable support.

Although I have illustrated and shall hereinafter describe my invention in connection with a shelf of the character mentioned, nevertheless it will be understood that as to 20 certain phases of my invention an application of this character is not essential, numerous features of my invention relating more broadly to any type of supported structure of the same general characteristics.

25 The type of shelf with which my invention is particularly applicable, comprises briefly a back frame and a shelf frame collapsibly arranged with respect thereto. The back frame is designed for application to a wall or 30 the like, and the shelf frame is so designed that when collapsed the entire device may be shipped in compact form and when opened the shelf frame may be caused to engage with the back frame in a suitable and efficient manner.

35 My invention contemplates the inclusion in the back frame of at least one upright frame element with which an extension arm may advantageously be associated for the 40 provision, when desired, of a supporting extension for the frame. It is one object of the invention to provide an extension arm which is so constructed and arranged as to be adjustably associative with the upright 45 frame element either in an upward or downward relationship, the upward relationship providing a supporting extension and the downward relationship permitting the arm to cooperate with the upright frame element 50 to brace the latter.

55 In one form of my invention, the extension arm is pivotally associated with the upright frame element and is provided at its free end with a transverse portion which may assume the form of a hook or the like. In this embodiment, the arm is so arranged and

constructed with respect to the frame element that when swung downwardly into relatively close relationship with respect to the frame element, the free end portion will 60 cooperate with the element to brace the latter.

Another object of my invention lies in the provision of means for retaining an adjustable extension arm in secure relative position with respect to the frame, when the arm is collapsed; and also is providing an arrangement wherein the collapsing of the extension arm will be effected in a compact manner. In this way, the shipment of the 70 device is greatly facilitated, and furthermore, in cases where the extension arm is not put to use, it may be caused to remain in compact form and neat relationship with respect to the frame. 75

In the embodiment previously mentioned, the transverse free end portion serves also to fulfill the foregoing objects of my invention.

In another embodiment, I provide an entirely independent and separate extension arm, such an arm being so constructed with respect to the balance of the frame as to permit removable association therewith in either an upward or downward relationship. 80 In this embodiment, the foregoing features of my invention are retained, and additional features are rendered possible. These additional features lie in the possibility of further increasing the staunchness of the 85 construction, and also in the possibility of providing still further variations with respect to the point of support. 90

The objects generally of my invention are to provide a collapsible device which is not 95 only simply made and hence inexpensive to manufacture, but which embodies extremely high qualities of firmness, strength, and flexibility of use.

For the attainment of the foregoing objects 100 and such other objects as may hereinafter appear or be pointed out, I have illustrated embodiments of my invention in the accompanying drawings, in which—

Fig. 1 is a front elevational view of the essential elements of a shelf, with parts broken away for the sake of clearness; 105

Fig. 2 is an end elevational view of the structure shown in Fig. 1, showing in dotted lines the general collapsible nature of the device; 110

Fig. 3 is a view similar to Fig. 2, showing

the extension arm in its downward relationship with respect to the frame;

Fig. 4 is a fragmentary rear view of an upper corner of the device, illustrating more clearly one detail of the construction;

Fig. 5 is a fragmentary perspective view of one end portion of a modified form of construction, showing in exploded relationship an independent extension arm for association therewith; and

Fig. 6 is a fragmentary end view similar to Fig. 3, illustrating the modified form of Fig. 5 with the extension arm in collapsed position.

Referring now to Figs. 1, 2, and 3, I have illustrated a frame shelf wherein the back frame comprises a bottom frame element 10, a top frame element 11, side frame elements 12 and 13, and struts 14 and 15 extending between the bottom and top elements 10 and 11.

This figure illustrates one feature of my invention, and it will be observed that the elements 12, 13, 14 and 15 comprise struts which are arranged in non-parallel arrangement. It will be observed that the pairs of struts 13, 15, and 12, 14, each extend downwardly from adjacent but spaced points on the top frame element 11. More particularly, referring to the elements 12 and 14, it will be noted that these elements extend downwardly from the points 16 and 17 respectively. The purpose of this construction will be presently described.

In Fig. 2, the general disposition of the shelf frame is shown, and this frame comprises briefly two side elements 18 and a series of properly arranged longitudinal elements 19. Adjacent to the outer ends of the side elements 18 are arranged pivotal struts or supports 20 which extend rearwardly and downwardly into pivotal association with the bottom frame element 10. The rear portions of the side elements 18 are constructed to provide hooks 21 adapted to engage over predetermined portions of the top element 11. In accordance with the present invention, these hooks 21 are so arranged as to engage respectively in the spaces between the spaced but adjacent points typified by the points 16 and 17, an engagement of this character lending great strength and staunchness to the assembled device.

The dotted lines in Fig. 2 indicate the general character of the device, it being observed that during shipment the device may be collapsed by releasing the hooks 21, pivoting the shelf frame downwardly and rearwardly, and swinging the elements 20 upwardly so as to collapse the entire device.

Referring now more particularly to the side element 13 illustrated in Figs. 2 and 3, it will be observed that its upper end extends slightly beyond the shelf frame and is provided with an opening 22 adapted to receive a screw or other fastening element 23. In one employ-

ment of the device, the fastening elements extending through the openings 22 serve to support the entire device upon a wall.

Slightly below the upper end of the side element 13 is a rivet 24 or the like designed for the purpose of associating the element 13 with the top element 11, and also to provide a pivot point for the extension arm 25. In accordance with the present invention, the arm 25 is arranged upon the forward surface of the element 13, the arrangement of elements upon the rivet 24 being thus, from rear to front, 13, 25, and 11.

In the embodiment illustrated in Figs. 2 and 3, the arm 25 is pivoted at one end to the element 13, i. e., at the rivet 24, and the free end of the arm 25 is provided with a transverse hooked end portion 26 extending rearwardly from the arm 25. The end portion 26 serves to support the entire device from a relatively higher point, when employment of the openings 22 is undesired. In this way, the arm 25, when up, provides a supporting extension for the back frame and for the entire device.

The arm 26 is of such a length that when it is swung downwardly into the position shown in Fig. 3, the free end portion 26 will lie adjacent to the free lower end portion of the element 13. The arm 25 will of course tend to assume a perfectly vertical position when it is swung downwardly, but by arranging it upon the forward surface of the element 13, I am enabled to swing the arm outwardly and cause the end portion 26 to brace itself against the lower forward surface of the element 13. In Fig. 3, the arm 25 is of such a length that this bracing will occur against the rivet 27 connecting the frame 13 and the lower frame element 10. As a result of this manipulation, a rigid end structure is provided constituted of the triangle formed by the element 13, the arm 25, and the end 26. The arm 25 is resiliently and frictionally braced with respect to the element 13, and will tend to hold the entire back frame against the wall in a staunch and secure manner. At the same time, the arm 25 is in this position compactly and neatly secured and instead of being wholly useless and cumbersome, it adds strength and good appearance to the device.

In connection with the downward positioning and bracing of the arm 25, it will be observed that the arrangement of the structure 14 and 15 in the diagonal manner shown, provides a complete structure which is peculiarly firm and rigid, being formed along a generally triangular plan.

In Figs. 5 and 6, I have illustrated a modification wherein the extension arm is provided as a separate and independent element. In this form of the invention, the side element 13' is provided with a T-shaped prong 28 at its upper end, and the arm 25' 130

is provided with a slot 29 adapted to engage the prong 28. It need hardly be pointed out that the width of the slot 29 is substantially equal to the width of the stem of the T 28, and that the association of the arm is effected by applying the slot 29 in a substantially horizontal direction to the prong 28 and thereupon swinging the arm through 90°, either upwardly or downwardly. After this 5 is effected, the cross bar of the T 28 will serve to retain the arm in association with the element 13'.

By the provision of a separable arm of this character, I am enabled to increase the 15 efficiency of the structure in numerous ways. The element 13' is provided with an opening 22' slightly below the upper end thereof. This opening may be employed in the same manner as the opening 22 of the previous 20 embodiment, whenever the extension arm 25' is wholly undesirable. At the extreme end of the arm 25' I provide an opening 30 which serves two functions. When the arm is in its upward relationship, the opening 30 is so 25 arranged as to register with the opening 22' so that a bolt or the like may be passed through these registering openings and thereby assure the proper vertical positioning of the arm 25'. On the other hand, when 30 the arm 25' is arranged in its downward relationship, the opening 30 fulfills the function which the openings 22' and 22 previously fulfilled; and incidentally, the opening 30 will in such an event be positioned in a further 35 variable relationship with respect to the shelf as a whole.

The latter arrangement is illustrated in Fig. 6, wherein the opening 30 is designed to receive a screw or the like to attach the 40 device to a wall. In this figure, it will also be observed that the arm 25', provided with an end portion 26', may advantageously be braced against the element 13', as in the previous embodiment, to lend strength to the 45 entire structure and to retain the back frame firmly against the wall. In this embodiment, I have found it advantageous to provide the arm 25' with a slight curvature 31 arranged in such a position as to clear the rivet which

attaches the element 13' to the top element 11 50 of the back frame.

It will be understood that as to certain phases of my invention, the provision of a braceable structure as shown in Fig. 6, is not essential. For example, the removable arm 55 25' embodies certain features which are quite independent from its ability to brace the element 13' as shown in this figure.

It will also be obvious that many changes 60 in the details herein described and illustrated for the purpose of explaining the nature of my invention may be made by those skilled in the art without departing from the spirit and scope of the invention as expressed in the appended claim. It is therefore intended that 65 these details be interpreted as illustrative and not in a limiting sense.

Having thus described my invention and 70 illustrated its use, what I claim as new and desire to secure by Letters Patent is—

A frame shelf comprising a main frame rigidly braced to rectangularity and embodying a top and a bottom bar and opposite side bars, an auxiliary frame embodying side bars pivoted at their lower ends to said bottom bar, 75 arms pivoted to the upper ends of the said auxiliary frame side bars and having hooks at their opposite ends proportioned to hook over the said top bar and form supporting 80 brackets and independent members each having a hook at one end to serve as securing means and each having at its opposite end means for connecting it with said main frame, 85 said connecting means being adapted to permit of said member extending electively above said frame as a support and of being reversed to a position below the top of said frame, said hook on each of said members being directed rearwardly with reference to the main frame, whereby when the members 90 are moved to reversed position, the hook on each member will be engaged between the member and the corresponding side wall of the main frame to serve as an auxiliary brace.

In witness whereof, I have signed and 95 sealed this specification this 24th day of March, 1927.

ROBERT E. MILLER.
